UNITED STATES PATENT OFFICE.

FREDERICK N. ROSS, OF PONTIAC, MICHIGAN, ASSIGNOR, BY MESNE ASSIGNMENTS, TO THE BUTTON-ATTACHING MACHINE CO., OF WATERBURY, CONNECTICUT, A CORPORATION OF CONNECTICUT.

OVERALL HARDWARE.

Application filed November 5, 1923. Serial No. 672,750.

To all whom it may concern:

Be it known that FREDERICK N. Ross, a citizen of the United States, residing at Pontiac, in the county of Oakland and State 5 of Michigan, has invented certain new and useful Improvements in Overall Hardware, of which the following is a specification.

This invention relates to overall hardware, and has for its object to provide improved art buckles and loops for overall straps.

It has been customary to make loops and slides of wire. They have also been made of flat sheet metal. So far as I am aware, 15 an article of this description has not heretofore been made of suitably formed corrugated bar stock, stamped as a unit from sheet metal. Especially is this true with the loop provided with pointed prongs. 20 Here the corrugated bar stock strengthens and reinforces the pointed prongs, as will be more fully described hereinafter.

In the drawings:

Fig. 1 is an elevational view showing the 25 lower portion of an overall suspender and exhibiting my improved metal loop and slide.

Fig. 2 is a vertical section taken on the line 2—2 of Fig. 1.

Fig. 3 shows how the button requires to be twisted in order to escape from the loop.

Fig. 4 shows the construction of the loop where the adjustment of the length of the strap is made positive and by means of the 35 same member which engages the button; the latter device is ordinarily called a buckle for a child's overalls.

Fig. 5 is a section on the line 5—5 of Fig. 4.

40 *a* designates a portion of the overalls to which is riveted a metal button *b*. The construction of the loop *c* is different from the ordinary sheet metal loop used on garters or similar purposes, or the wire loops 45 that are used on similar articles. The metal is punched out in two separate places, a **T** punch being taken at *d* and an elongated slot punching at *e*. This gives an intervening cross bar *f*. This completely

50 separates the metal button from the cloth webbing *g* of the strap. Hence, the button does not abrade the webbing and is constricted in a much smaller slot than would be the case where the webbing and the

button pass through the same slot. It 55 requires considerable twisting of the button, as plainly is evident in Fig. 3, in order to allow the button to escape. Consequently, the button is much more securely held in the loop than is the case with the ordinary loop 60 construction. This is quite essential with overall suspenders, as obviously the strap is not always under tension as is the case with garters. Hence, when one bends or slouches down in a chair, very often all tension is 65 relieved on the strap and the button can very easily escape through the large slot used at the top of the loop.

These loops and the slides *h* are ordinarily 70 made of wire. However, one of the important features of my invention is that I construct these of corrugated stamped bar stock in which the entire article is punched and formed out. This makes a very much improved piece of hardware from an art standpoint, over the wire constructions of the prior art, or over the ordinary stamped metal loops and slides. The corrugated 75 bar stock permits of the use of lighter gauge metal, and still attains the strength 80 that is requisite. Furthermore, it makes a much improved appearance. The edges are turned in and this is very advantageous, especially with the slide as this forms a sharp line or angle contact that is calculated 85 to dig into the straps as is clearly evident in Fig. 2, and thereby more securely holds the slide from slipping by reason of establishing sharp angles in the strap. In order 90 to carry out this plan of establishing sharp angles in the strap to prevent the slide slipping, the corrugation of the center bar of the slide designated *j* is reversed.

In the slide shown in Fig. 4, one of the 95 center bars *i* is reversed for the same purpose. This slide is one coupled up with my improved loop. This is ordinarily known as the child's buckle for a child's overalls, and the slide is further provided with prongs *k* which are struck out of the stock 100 of the center corrugated bar which is not reversed. These prongs are directed inwardly, as a sort of continuation of the arc on which the bar is corrugated. This very materially strengthens the prongs for 105 the reason that the prongs and stock of the bar to which it is attached are directed in substantially the same direction. Hence,

any stress tending to bend the prong is directed along the length of the prong and the stock which supports it.

In overall hardware, it will be apparent from an examination of the drawings, that loop members made of this corrugated bar stock stamped out as a unit in the way I have described, make a very simple, effective and strong loop. From an artistic standpoint, this is a great improvement over the hardware that has heretofore been used with overalls. Wire and flat metal stampings have been used on loops before, but they do not compare with my hardware from an artistic standpoint. The corrugated bar stock appeals to the esthetic sense, when properly stamped out by clean cut dies. This is especially true as the cross section of the stock very nicely harmonizes with the relatively short radii curves that are apparent especially in the button loop, as will be seen from examining Fig. 1. There is nothing ornate about the design, but this harmonizing of the cross section with the relatively short radii of the button loop gives an artistic harmony which appeals to the esthetic sense. As has often times been remarked, some of the most appealing designs are those which are emphatically simple, yet possess such a harmony of curve and proportion as to make a striking appeal.

It will be noticed that the T slot *d* which is also referred to as the button slot, has the stem of the T tapered. This serves to wedge the button neck into the button loop,

and tends to prevent the button from escaping. For the purpose of reference in the claims, either the slide or the loop per se may be considered a loop member, as both are provided with loops. It will therefore be taken that I refer to either member by terms of general significance, and to one specific member when I use a term of narrower significance.

What I claim is:

1. In overall art metal hardware, a loop member comprising a stamped corrugated bar stock with prongs stamped out of one of the bars and projecting at an angle which forms an approximate continuation of the arc of the corrugation for the purpose of strengthening the prongs.

2. In overall art metal hardware, a loop member constructed of open corrugated bar stock with the outline frame having the convexity of the corrugation on the face of the loop while the center cross bar has the open concavity of the corrugation on the face of the loop, for the purpose specified.

3. In overall art metal hardware, a loop member in the form of a single unit stamping of corrugated bar stock with the outline frame having a convexity of the corrugation on the face of the loop and the center cross bar having the open concavity of the corrugation on the face of the loop, for the purpose set forth.

In testimony whereof he has affixed his signature.

FREDERICK N. ROSS.
